TWO-CYCLE VALVED PISTON

Application filed December 28, 1928. Serial No. 329,022.

The principal objects of the invention are to effect a rapid opening and closing of the intake and exhaust ports in a two cycle engine cylinder, thereby obtaining a lead and a lag 5 on the opening and closing of said ports.

A further object is to enable the use of larger port openings thereby increasing the efficiency of the engine.

The principal feature of the invention consists in the arrangement of a valving element 10 supported by the piston rod and operated through the swinging action of the piston connecting rod to effect the opening and closing of ports in the cylinder.

15 In the drawings, Figure 1 is a longitudinal mid-sectional view of a portion of the cylinder, piston and valve constructed in accordance with this invention.

Figure 2 is a sectional view of a cylinder 20 and piston showing a slightly modified form of connecting rod.

Figure 3 is a similar sectional view showing a further modification of the valving mechanism.

25 Figure 4 is a transverse section of a cylinder constructed as shown in Figure 3 taken through the line 4—4 of Figure 3.

Figure 5 is a transverse sectional view taken through the line 5—5 of Figure 3.

30 In the form of the invention illustrated in Figure 1 the cylinder 1 is provided with an arrangement of intake ports 2 at one side and exhaust ports 3 on the other side.

The piston 4 supported on the connecting rod 5 is arranged within a sleeve or secondary piston 6 which fits with a snug sliding fit in the cylinder.

35 The sleeve piston 6 is provided with ports 7 adapted to co-operate with the inlet ports 2 and with ports 8 adapted to co-operate with the exhaust ports 3.

The ports 7 and 8 are offset in their longitudinal arrangement on the sleeve.

40 The sleeve 6 is provided with a circular boss 9 arranged to extend inwardly below the skirt of the piston 4.

A stud arm 10 projects rigidly from the connecting rod 5 in a direction substantially 45 at right angles to the centre line of the con-

necting rod and in the direction of the swinging movement of the connecting rod.

It will be understood that as the crank shaft revolves it reaches a point in its downward throw where there is very little downward movement of the piston but the connecting rod swings transversely through a considerable arc while the piston is practically stationary.

45 The sleeve 6 is so arranged on the piston that when the main crank swings in its downward travel the piston 4 will move below the opening of the port 3 while the ports 8 in the sleeve valve 6 still retain the port closed.

The transverse swinging of the connecting rod which produces very little movement in the piston does however operate through the stud arm 10 to move the sleeve 6 downwardly 50 very rapidly.

55 This opens the exhaust port and the continued movement moves the sleeve to a position to open the intake port and eventually to close the exhaust while the piston is practically stationary or moves to a very short distance longitudinally of the cylinder.

70 The upward movement of the piston cuts off the intake port and at the top end of the stroke the position of the sleeve is returned ready for the rapid action thereof at the bottom end of the stroke when the piston having reached practically the maximum of its travel, the port is then opened to free the exhaust gases. The action then continues as described to open the intake port. This operation of a secondary piston to control the valve ports accomplishes a very marked improvement in the operation of a two cycle engine.

75 The invention as outlined is capable of being developed along many different forms of structure and in the form shown in Figure 2 the sleeve or secondary piston 11 is provided with a lug 12 to which a secondary connecting rod 13 is pivotally secured. This connecting rod is connected at its lower end to the crank 80 on which the main connecting rod 14 is mounted.

85 The action of the connecting rod 13 being connected to the sleeve on a considerable distance offset from the centre of the cylinder 90

will cause substantially the same movement as that described in connection with the structure illustrated in Figure 1.

A further application of the invention is illustrated in Figures 3, 4 and 5 in which the piston sleeve 14' extends beyond the head end of the main piston 15 and is provided with circumferentially spaced ports 16 and 17 which are adapted to be brought into register with the cylinder ports 18 and 19 respectively through an oscillating action.

This oscillating movement is effected by the arrangement of a stud 20 extending laterally from the connecting rod in a direction transverse to the swinging movement of the connecting rod and said stud is provided with a ball end 21 which enters a circular recess 22 in the lower end of the sleeve.

A cylinder is provided with intake and exhaust manifolds 24 and 25 respectively which extend part way around the cylinder.

It will be seen that as the connecting rod swings through the operation of the crank shaft the laterally extending stud will carry the sleeve with an oscillating movement to effect the opening or closing of the ports while the main piston is in a practically stationary position.

The operation of this double piston is extremely simple. It operates longitudinally of the cylinder in the usual manner but because of the relatively movable ports thereof a very quick operation of the valving function is brought about at the end of the stroke which is most desirable as the exhaust ports are opened quickly to their maximum position allowing the rapid escape of the gases of combustion and the inlet ports are likewise more effectively controlled.

What we claim as our invention is:

1. In a two cycle internal combustion engine, the combination with a cylinder having inlet and exhaust ports, a piston operating in said cylinder, a connecting rod operatively connected with said piston and operating in a fixed plane, and a sleeve surrounding said piston and adapted to move separate from the piston to control the exhaust and inlet ports, of means carried by said connecting rod and extending transversely of said fixed plane of operation of the latter shaft for controlling the movement of said sleeve.

2. In a two cycle internal combustion engine, the combination with a cylinder having inlet and exhaust ports, a piston operating in said cylinder, of oscillatable means movable with said piston for controlling said exhaust and inlet ports, and a stud extending from said connecting rod in a direction transversely of the plane of operation of the latter and operatively engaging said movable member to impart an oscillating and reciprocal movement thereto to control said ports.

3. In a two cycle internal combustion engine, the combination with a cylinder having

inlet and exhaust ports, a piston operating in said cylinder, a connecting rod operatively connected with said piston and operating in a fixed plane, of an oscillatable sleeve encircling said piston and adapted to be moved separate from the piston to control the exhaust and inlet ports, said sleeve having a socket therein arranged at an angle to the plane of operation of said connecting rod, and a stud rigid with said connecting rod and extending laterally of the plane of operation of the connecting rod into said socket and operating said sleeve with a combined oscillating and reciprocal movement.

4. In a two cycle internal combustion engine, the combination with a cylinder having inlet and exhaust ports, a piston operating in said cylinder, and a connecting rod operatively connected with said piston and operating in a fixed plane, of an oscillatable sleeve encircling said piston and adapted to be moved separate from the piston and having ports therein adapted to register with the cylinder ports, and an operating extension rigid with said connecting rod and extending laterally in angular relation to the plane of operation of the latter and co-operating with the sleeve to impart a combined reciprocable and oscillating movement to said sleeve to control the opening and closing of the cylinder ports.

5. In a two cycle internal combustion engine, the combination with a cylinder having inlet and exhaust ports, a piston operating in said cylinder, a connecting rod operatively connected with said piston and operating in a fixed plane, of means operating with said piston and movable in relation thereto for controlling said exhaust and inlet ports, and a lateral extension on said connecting rod angularly disposed with relation to the plane of operation of the latter and operatively engaging said controlling means at a point out of alignment with said plane of operation of said connecting rod to effect the operation of the controlling means.
